UNITED STATES PATENT OFFICE

RICHARD M. CROSBY, OF TACOMA, WASHINGTON

SPARK ARRESTER

Application filed May 18, 1931. Serial No. 538,115.

My invention relates generally to spark arresters, and more particularly to apparatus of this type for use in steam locomotives. My present invention is an improvement upon 5 the apparatus shown in my prior Patent No. 1,108,710, granted August 25, 1914.

An object of my invention is to provide a more efficient form of baffle or retarding grating to delay the movement of live cinders 10 or sparks carried by waste gases in their passage from the locomotive fire box to the smoke stack.

A further object of my invention is to provide an improved baffle means to cause the 15 furnace gases to move through a tortuous channel between the furnace and the stack, thereby creating turbulent whirling and eddying of the gases, with the result that the larger sparks will be driven against the deflecting plates, broken up, and extinguished.

A further object of my invention is to provide a means of preventing sparks and cinders from escaping around the ends of deflection vanes.

25 A further object is to provide a generally improved spark arresting means for steam locomotives which is simple in construction, durable, which is self-cleaning, and which may be economically installed in a standard 30 locomotive.

Other objects will appear from the following description, reference being had to the accompanying drawing, in which

35 Figure 1 represents a vertical, longitudinal section of the smoke box of a locomotive embodying my invention;

Figure 2 is a front elevational view with the head plate removed, portions of the parts being broken away to show detailed construction thereof;

Figure 3 is a vertical sectional view taken on the line 3—3 of Fig. 2; and

40 Figure 4 shows my invention diagrammatically in relation to other parts of the locomotive.

The spark arrester, designated generally as 10 (Fig. 4), is located within the smoke box 12 of the locomotive. The products of combustion pass from the fire box 14 through 45 the fire tubes 16 into the lower portion of the

smoke box 12, are acted upon by the spark arrester 10 of my invention and pass outwardly through the stack 18.

As shown in greater detail in Fig. 1, the smoke box 12 is divided into three compartments 20, 22 and 24, the compartment 20 being formed by the boiler head plate 26 and sloping plate 28. The plate 28 is riveted or otherwise suitably secured at its upper end to the top plate 30 of the smoke chamber, and has its lower end similarly secured to a horizontal transverse plate 32 which embraces the exhaust steam nozzle 34. The plates 28 and 32 extend transversely the full width of the smoke box and are suitably secured to the shell 36 of the smoke box. The plate 32 has a forwardly and downwardly extending flange portion 38 which carries an angle iron 40. The compartment 22 is formed by the smoke box shell 36, the front head plate 42, and bank of deflecting vanes 44.

The bank of deflecting vanes 44 is supported by a pair of curved angle irons 46 and a pair of supporting bars 48, and the curved angle irons 46 may be riveted or welded to the smoke box shell 36, while the supporting bars 48 are secured at their upper ends to an angle 50 and at their lower ends to the angle 40. A plurality of vanes 52 are supported in echelon, extending transversely across the smoke box. Each of the vanes 52 has riveted thereto four strips 54. The strips 54 and hence the vanes 52 are secured to the angle irons 46 and supporting bars 48 by bolts 56 which project through the upper and forward edges of the vanes 52, strips 54, a spacer 58, and through the lower and rearward end of the next adjacent strip 54. The lower rearward edge of each of the vanes 52 is curved downwardly and forwardly as at 60 to 65 form a curved deflecting surface. A plurality of transverse apertures 62 are thus formed between the lower edges of the upper vane and the upper edge of the lower vane. Filler plates 64 have their upper edges shaped to conform generally to the lower surfaces of the vanes 52 and are welded or otherwise secured to the transverse portions of the angle irons 46.

A small amount of clearance is preferably left between the upper edges of the 70 75 80 85 90 95 100

filler plates 64 and the lower surfaces of the vanes 52 to permit relative movement between these parts due to temperature changes.

A segment-shaped plate 66 is suitably secured to the mounting ring 68 and serves as a support for a sloping baffle plate 70, the rearward edge of which is supported by a vertical angle 72 which may be welded or otherwise suitably secured both to the smoke box shell 36 and the plate 70. If desired, the plate 66 may be apertured to permit circulation of a portion of the flue gases therethrough. A deflecting plate 74, the rearward edge of which is curled downwardly as shown at 76, is adjustably secured to the baffle plate 70 by a plurality of bolts 78. The bolts project through suitable holes in the plate 70 and slots 80 formed in the deflecting plate 74. The deflector plate 74 may thus be adjusted to suit the particular operating requirements of the boiler and furnace with which it is used.

In operation, the soot-laden flue gases discharged from the fire tubes 16 are in part projected against the plate 28, thereby partially collecting together the soot particles. The gases pass forwardly into the compartment 22 where they are separated into two streams, one flowing upwardly directly through the space formed between the deflector plate 74 and the bank 44 of vanes, the other flowing into the space formed by the plates 66, 70 and 74. The former stream travels at high velocity and is in part projected against the lower surfaces of the vanes 52 and the solid particles thus broken up by impact and temporarily arrested. The deflector plate 74 greatly restricts the path for the upward flow of the gases in the compartment 22, with the result that the passage of gases between the deflector plate 74 and the bank of vanes 44 is greatly accelerated. The heavier solid particles carried by the gas thus acquire high momentum and do not readily change their direction of motion so as to enable them to pass outwardly through the apertures 62. A large majority of the larger solid particles will strike the lower surfaces of the vanes 52 and be broken up or deflected forwardly against the front head plate 42 and drop upon the baffle plate and deflector plate 74, upon which they will be carried rearwardly by the swirling currents of gas and again get into the high velocity stream passing between the rearward edge of the deflector plate 74 and the bank of vanes 44. The larger particles will thus have repeated chances of being broken up. Each of the curled portions 60 of the vanes 52 checks the passage of the heavier particles and sets up an eddy or swirling turbulence which further delays the exit of the solid particles through the apertures 62. The gases thus freed from the heavier particles carry the smaller fragments thereof through the apertures 62, where they

are forced outwardly through the stack 18 by the jet from the exhaust nozzle 34.

Since the flue gases will not ordinarily support combustion, some of the larger particles, if not broken up in the smoke box, will cool off sufficiently so that when ejected from the stack 18, they will not ignite. The particles which more readily pass through the apertures between the vanes 52 will ordinarily be of such small size that although they may be sufficiently hot to be ignited will be rapidly consumed as soon as they reach the atmosphere.

The secondary stream of flue gases is projected against the plate 66 and thereby deflected upwardly against the baffle plate 70 and deflector plate 74. These plates thus cause a circulatory turbulent movement of the gases, with the result that the heavier burning particles in the gas are thrown outwardly by centrifugal force against the plates and thereby broken into smaller particles. The curved lip 76 of the deflector plate 74 aids in inducing this whirling motion. The second stream is thus freed from larger burning particles and is drawn with the remaining gases through the spaces between the vanes 52.

Since the flue gases do not readily support combustion, a large proportion of the burning particles are soon extinguished. Thus, even though the length of time that these particles are delayed in their passage through the compartment 22 is comparatively short, there will be sufficient time for a large majority of the sparks to become extinguished. Since the particles are broken up to a great extent, they will, even though still burning when they have passed through the bank of vanes 52, be more readily extinguished by the steam jet and will burn up more rapidly when they are ejected into the atmosphere.

By adjustment of the deflector plate 74, the velocity at which the flue gases pass upwardly against the upper vanes may be varied to secure the most efficient operation of the spark arrester consistent with the maintaining of a low back pressure on the flue gases.

The end filler plates 64 prevent the passage of the gases around the ends of the vanes 52 and thereby prevent the large burning solid particles from escaping directly from the compartment 22.

The plate 66 protects the front end door plate 42 against the direct blast of flue gases. The direction of the flow of gases is roughly indicated by the arrows shown in Fig. 1.

While I have illustrated and described a preferred embodiment of my invention, many modifications may be made without departing from the spirit thereof, and I do not wish to be limited to the precise details set forth but desire to avail myself of all changes within the scope of the appended claims.

I claim:

1. In a locomotive boiler, a channel through which the products of combustion pass away from said boiler, a series of deflecting vanes extending in substantially a plane across said channel, said vanes lying in parallel planes which are inclined to the plane of the series, the plane of the series being upwardly inclined toward one wall of said channel, each of said vanes having its lower edge spaced from the upper edge of the next adjacent vane to form apertures for the flow of the gases of combustion, and adjustable baffle means projecting into said channel and reducing the cross sectional area thereof at a point adjacent said series of vanes.

2. In a smoke box having a passageway for flue gases, spark arresting means comprising a plurality of spaced deflecting vanes forming apertures extending transversely across the smoke box, baffle means projecting into said passageway and materially diminishing the cross sectional area thereof at a point adjacent said vanes, and means for adjustably positioning a portion of said baffle means to vary the cross sectional area of the passageway for the gases.

3. In a locomotive, the combination of a smoke box having a circuitous passageway for the flow of flue gases, a plurality of deflecting blades arranged in echelon across said passageway, and a baffle materially reducing the cross sectional area of said passageway, said baffle comprising a fixed plate and an adjustable plate, said latter plate having its edge projecting into said passageway curled to aid in imparting a whirling motion to the flue gases projected thereagainst.

4. In a spark arrester for locomotives, the combination of a smoke box having a circuitous passageway therethrough, a plurality of deflecting vanes extending transversely across said passageway, said vanes lying in substantially parallel equidistant inclined planes with the lower edge of each of the upper vanes lying substantially in the vertical plane which passes through the upper edge of the adjacent lower vane, each of said vanes having its lower edge curled inwardly so as to form a substantially cylindrical sector, and filler plates positioned beneath said vanes to prevent escape of gases around the ends of said vanes, said filler plates being positioned in a plane substantially perpendicular to the planes of said vanes and conforming to the shape thereof but spaced a minute distance therefrom.

5. In a locomotive having a smoke box with a passageway for the flow of flue gases, a grating extending transversely across said passageway, said grating providing transverse apertures for the flow of gases and deflecting surfaces, a baffle inverted L-shaped in cross section positioned transversely across said passageway, and an extension plate ad-

justably secured to said baffle and forming therewith a substantially continuous plate for reducing the effective cross sectional area of said passageway and causing a turbulent flow of the flue gases.

In witness whereof, I hereunto subscribe my name this eleventh day of May, 1931.
